UNITED STATES PATENT OFFICE.

LEONARD E. HURST AND JAMES F. MILLER, OF DETROIT, MICHIGAN.

RAIL FASTENER.

Application filed April 27, 1923. Serial No. 634,954.

To all whom it may concern:

Be it known that we, LEONARD E. HURST and JAMES F. MILLER, citizens of the United States, and residents of Detroit, Wayne County, Michigan, have invented a new and Improved Rail Fastener, of which the following is a specification.

This invention relates to means for attaching rails and other beams to the flanges 10 of beams and channels and to other supports, and its object is to provide a device of this character which will rigidly unite the rail or other beam to its support, which will not extend beyond the edges of the 15 base of the rail or other beam, which can be produced as a stock device and is freely adjustable, and which can be produced at low cost.

This invention consists in combination 20 with a flanged rail or other beam and a support therefor, of a bolt transversely perforated or otherwise deformed at one end and preferably threaded at the other, the bolt being adapted to extend through the 25 supporting beam, channel or other support into a hole drilled into the rail or other beam through the base and cutting the web thereof, a pin connected to and extending transversely of the bolt above the base of 30 the supported member, and means, preferably a nut, at the opposite end of the bolt to secure the bolt to the support.

It further consists in the details of construction illustrated in the accompanying 35 drawing and particularly pointed out in the claims.

In the drawing, Fig. 1 is a transverse section of a conveyer trough and of the rails for supporting the conveyer flights. Fig. 2 40 is a longitudinal section through the rail fastener. Fig. 3 is a perspective of a locking pin and Fig. 4 is a perspective of a bolt.

Similar reference characters refer to like parts throughout the several views.

Fig. 1 of the drawing shows a cross section of a trough having a bottom 1 on which rest the channel bars 2 whose upper flanges 3 are perforated at intervals to receive bolts 4 whose lower ends are preferably threaded and whose upper ends are perforated or otherwise deformed to receive the transverse pins 5. The rails 6 rest on the flanges 3 and holes are drilled through the bases 7 of the rails, preferably along 55 their middle lines, cutting the webs 8 to admit the ends of the bolts 4. Pins 5 extend

through the perforations in the bolts and are of sufficient length to rest on the flanges of the bases of the rails.

As the upper surfaces of these flanges 60 slope downwardly and outwardly, I prefer to form the pins to fit these surfaces, their lower sides 10 sloping accordingly to the slopes of the top sides of the bases of the rails. This is of advantage, for after stress 65 is placed on a bolt by its nut 11, it is practically impossible to remove the pin 9. We prefer to place beveled washers 12 and lock washers 14 between the nuts 11 and the inclined lower surfaces of the flanges 3. 70

The bolts 4 are easily made of any desired length and they can be perforated by punching while hot. The pins 5 may be punched cold from sheet metal of the proper thickness. 75

The details of construction and the proportions of the parts may all be changed by those skilled in the art without departing from the spirit of our invention as set forth in the following claims. 80

We claim:—

1. A fastener comprising a bolt extending into a hole formed in the base and web of a rail or other beam, a pin attached to the bolt and extending across the upper end thereof and engaging the upper sides of the flanges of the bar, and a nut on the lower end of the bolt. 85

2. A fastener to secure a rail to the outer surface of a flange of a beam where the flange of the beam and the base and web of the rail are formed with alined holes, a bolt extending through said hole in the flange of the beam and into the hole in the base and web of the rail, the end of the bolt 90 in the hole in the rail being transversely perforated, a pin extending across in said perforation and engaging the upper surface of the rail base, and means to secure the bolt to the flange of the beam. 95

3. A fastener to secure a rail to the outer surface of a flange of a beam where the flange of the beam and the base and web of the rail are formed with alined holes, a bolt extending through said hole in the flange 105 of the beam and into the hole in the base and web of the rail, the end of the bolt in the hole in the rail being transversely perforated, a pin extending across in said perforation and engaging the upper surface of the rail base, and means to secure the bolt to the flange of the beam and embodying a 110

washer to fit the lower side of the flange of the support and a nut on the bolt on the opposite side of the washer from the flange.

4. A fastener to secure a rail to the outer surface of a flange of a beam where the flange of the beam and the base and web of the rail are formed with aligned holes, a bolt extending through said hole in the flange of the beam and into the hole in the base and web of the rail, the end of the bolt in the

hole in the rail being transversely perforated, a pin extending across in said perforation and engaging the upper surface of the rail base, and means to secure the bolt to the flange of the beam, said pin having one side inclined in two directions to fit the upper surface of the rail base and be held thereby in said perforation in the bolt. 15
